CAN PUNCTURING SPOUT

Ozro N. Wiswell, Los Angeles, Calif., assignor to
 Swingspout Measure Co., Los Angeles, Calif.,
 a corporation of California

Application August 10, 1942, Serial No. 454,270

4 Claims. (Cl. 222—89)

1

This invention relates to devices for opening containers and relates more particularly to devices for opening cans and for dispensing the contents therefrom. A general object of this invention is to provide a device of this character that is adapted to handle or dispense very light penetrating fluids without leaking.

Many products are marketed in sealed containers or cans and are adapted or intended to be used or dispensed directly from the can. For example, the anti-freeze compounds for use in automobile and truck radiators are commonly sold in sealed cans to be directly poured into the radiator when the can is opened. Can opening and pouring devices which I will herein refer to as can spouts are widely used to open sealed cans of oil, anti-freeze compounds, and the like. The can spouts will handle or dispense the contents of a can of oil and like fluids without leaking but anti-freeze compounds are very light and penetrating and when they are dispensed from the regular can spouts there is considerable leakage.

An important object of this invention is to provide a can spout that is adapted to handle or dispense very light penetrating fluids without leaking.

Another object of this invention is to provide a can spout of the character referred to embodying a sealing member or washer for sealing with the bead and the end of the can around the opening therein to prevent the leakage of fluid around the handle and spout portion of the device.

Another and important object of this invention is to provide a can spout of the character mentioned embodying novel means for holding the sealing member or washer in tight sealing cooperation with the can. The sealing washer is formed of yielding resilient material to readily conform to and seal with the can and the resiliency of the washer tends to cause the can spout to back away or assume a loosened position where the liquid may leak. The invention includes a novel and very effective means for holding the device in the full-in position where the washer is compressed and in tight engagement with the can so that there is no leakage of even very light liquids.

Another object of this invention is to provide a can opening and dispensing device of the character mentioned in which the means for holding the can spout in the full-in position is in the form of a latch having positive dependable cooperation with the bead of the can. The latch is positive and holds the can spout in the position on the can where it is ready to dispense or pour

2

the contents. The latch, in addition to maintaining the sealing means effective, prevents detachment and dislocation of the can spout even when the can spout is employed as a handle to lift, carry and manipulate the unemptied can.

Another object of this invention is to provide a can spout embodying means for effectively sealing with the end walls of containers or cans of substantial capacity and when such end walls are corrugated or irregular. It has been found that when the cutter of a can spout is forced through the end wall of a can of substantial capacity or diameter the wall distorts or bends in many cases and the can spout does not obtain effective sealing cooperation with the bent wall. The present invention provides a yielding conformable sealing washer that effectively seals with and conforms to can walls that are distorted, corrugated, beaded or otherwise non-flat to maintain an effective seal with the can.

Another object of this invention is to provide a can spout of the character referred to in which the latch means for holding the device in the position where the sealing washer is in tight cooperation with the can wall is adapted to latch with the can bead in two or more positions of the can spout so that the sealing washer is held effective even though the can spout is not moved to its full "down" position and even though the bead of the can may vary in thickness or bear different relationships to the top can wall. The latch means embodied in the device of the invention may have two or more vertically spaced latch noses or latch tongues for cooperating with the can bead in different positions of the can spout to assure the correct maintenance of the sealing washer in sealing engagement with the can wall under practically all operating conditions.

Another object of this invention is to provide a can spout of the character referred to in which the latch automatically latches with the can bead to thereafter maintain the sealing means effective but may be readily released from the bead to permit withdrawal of the can spout from the can.

A further object of this invention is to provide a device of the character mentioned in which the sealing means and latch means are simple and inexpensive and are readily embodied in the can spout structure.

The various objects and features of my invention will be fully understood from the following detailed description of typical preferred forms and applications of my invention, throughout

which description reference is made to the accompanying drawings, in which:

Fig. 1 is a side elevation of the can or container with the can spout of the invention in position thereon. Fig. 2 is an enlarged vertical detailed sectional view of the can spout in the operative position on the can. Fig. 3 is a horizontal detailed sectional view taken as indicated by line 3-3 on Fig. 2. Fig. 4 is an edge or side elevation of the latch removed from the can spout. Fig. 5 is a top or plan view of the latch taken as indicated by line 5-5 on Fig. 4. Fig. 6 is a horizontal detailed sectional view taken as indicated by line 6-6 on Fig. 4. Fig. 7 is an enlarged vertical detailed sectional view of another form of latch that may be embodied in the device. Fig. 8 is an enlarged side elevation of still another form of latch which has series of noses or tongues for latching with the bead. Fig. 9 is an elevation view of the inner side of the latch shown in Fig. 8. Fig. 10 is a horizontal detailed sectional view taken as indicated by line 10-10 on Fig. 9. Fig. 11 is an edge or side elevation of still another form of latch and Fig. 12 is an elevation view of the inner side of the latch shown in Fig. 11.

The device of the present invention may be said to include, generally, a body comprising a combination handle and spout 10 and a guide 11, a cutter 12 adapted to be forced through the end wall X of the can C to cut a pouring opening therein, a sealing washer 13 on the body for sealing with the can around the pouring opening and releasable means 14 for maintaining the body in the position where the washer 13 tightly seals with the can C.

The body of the device is an elongate element made up of the combined handle and spout 10 and guide 11. The handle and spout 10 is longitudinally curved upwardly and outwardly considering the device to be in the position illustrated in Figs. 1 and 2. The handle and spout 10 is shaped and proportioned to be readily grasped and held and to be readily inserted in the filling openings of radiators, crank cases, etc. The outer or convex side of the spout 10 has a plurality of longitudinally spaced grooves or depressions 15 and the inner or concave side of the spout has spaced ribs 16 to provide a better grip and to prevent the spout from slipping or tipping when engaged in the liquid receiving opening. The handle and spout 10 is generally cylindrical in transverse cross section and is preferably of slightly outwardly diminishing fluid capacity. In the form of the invention illustrated the handle and spout is sectional, being formed of inner and outer sections A and B joined or connected along their longitudinal edges by suitable latch joints 17.

The guide 11 continues or extends from the lower end of the handle and spout 10 and is operable to engage or cooperate with the side wall of the can C during the cutting of the pouring opening to guide the cutter 12 so that it forms the pouring opening immediately adjacent the bead D which connects the end wall X and the side wall of the can. In the preferred construction the guide 11 is an integral extension of the inner section A of the combination handle and spout 10. The guide 11 is shaped to conform generally to the side walls of the cans for which the device is intended. In the case illustrated, the guide 11 is an elongate transversely curved part suiting the device for opening the usual cylindrical cans. The device is not restricted for

use on cylindrical cans but is adapted to open square cans and cans of other shapes. When employed to open polygonal cans the cutter 12 is forced through the top can wall at one of its corners and the guide formed as above described rides down the corner of the can. In practice, the guide 11 is of substantial length and its width is somewhat greater than the diameter of the spout 10 so that a shoulder 18 occurs where the guide joins the section A. The lower end of the guide 11 is rounded or bevelled.

The cutter 12 is adapted to be forced or driven through an end wall X of the can C to cut the pouring or draining opening therein. In the preferred construction the cutter 12 is substantially U-shaped in transverse cross section and is provided with downwardly and outwardly inclined longitudinal edges 19 which merge with the entering point portion 20 of the cutter. The curved outer portion or side of the U-shaped cutter 12 opposes and is spaced from the can engaging inner face of the blade or guide 11. The side walls 21 of the cutter are vertical and generally parallel and are provided near their upper ends with lateral windows or openings 23 to permit the fluid in the can C to readily drain out through the U-shaped cutter into the spout 10. The entering point portion 20 of the cutter 12 converges to a sharp point for piercing the can wall X and this point portion 20 preferably slopes downwardly and inwardly so that it starts through the wall X at a point a short distance from the bead D. A shank 24 extends from the upper end of the cutter 12 and enters the combination handle and spout 10. As best illustrated in Fig. 2 of the drawings the side walls 21 of the U-shaped cutter 12 extend some distance into the spout and the shank 24 is a reduced extension continuing upwardly from the side walls to extend a substantial distance into the curved spout. The shank 24 is longitudinally curved to correspond to the curvature of the handle and spout 10. A screw 25 is passed through registering openings in the spout 10 and shank 24 and a nut 26 is threaded on the screw to engage in the shank 24 and thus secure the cutter to the body. A lock washer or the equivalent may be engaged under the nut 26 to prevent its unthreading. As illustrated in Fig. 3 of the drawings the extreme lower end of the combination spout and handle 10 has flat parallel side wall portions 27 and the side walls 21 of the cutter 12 tightly engage between these wall portions 27 to secure the cutter 12 against lateral forces. The lower end of the spout section B is further provided with a lip 28 which extends inwardly between the parallel side walls of the cutter 12.

The washer 13 is provided to seal with the walls of the can C around the pouring opening, cut therein by the cutter 12, to prevent the liquid from leaking and running down the exterior of the spout 10 when the can C is inverted to dispense or pour out the contents. The washer 13 is arranged at the base of the handle and spout 10 to be at or adjacent the portion of the device where the blade-like guide 11 joins the spout. The body of the device is constructed to effectively retain the sealing washer 13. A transverse or generally horizontal flange or shoulder 29 is provided on the lower end of the spout 10. The flange 29 may be a separately formed part secured to the spout section B by a lip or flange 30 that is soldered, welded or otherwise fixed to the exterior of the spout section B. The flange 29 straddles the spout 10 to rest on the above mentioned flange

18. The shoulder 29 may be soldered, welded, or otherwise sealed to and secured to the shoulder 18. The outline or shape of the shoulder 29 may vary in different applications of the invention. In the case illustrated, the flange 29 has straight parallel ends and a straight outer edge, the ends being spaced from and parallel with the wall portions 27 of the spout section B. A lip 31 extends along the edges of the flange 29 and projects downwardly to assist in retaining the washer 13. In the preferred construction the flange 29 and its lip 31 slope downwardly and inwardly toward the center of the can C.

The washer 13 is a yielding resilient member engaging around the upper end of the cutter 12 to seal with the cutter and to seal with the top of the can C. It is preferred to construct the washer 13 of a soft yielding material having a substantial degree of resiliency. For example, the washer may be formed of sponge rubber, synthetic sponge rubber, or the like. The washer 13 is shaped to seat on and bear upwardly against the shoulder 29, to fit closely within the flange 31 and to bear against the inner face of the guide 11. An opening 32 is provided in the washer 13 and closely receives the upper portion of the cutter 12 and the wall parts 27 and lip 29 of the spout section B. Fig. 3 of the drawings illustrates the manner in which the washer 13 closely fits within the flange 31 and closely fits about the cutter 12 and the parts 27 and 28. The upper portion of the guide 11 has a central longitudinal internal groove 33 which continues into the lower portion of the spout 10. The upper side and the outer surface of the washer 13 have a projection or rib 13a which occupies the upper portion of the groove 33. The washer 13 is tightly fitted or pressed into the flange 31 and the upper portion of the groove 33. This serves to secure or retain the washer 13 in place although the washer may be cemented, vulcanized or otherwise secured if desired.

In accordance with the invention the washer 13 is of substantial thickness and projects downwardly beyond the flange 31 to have a broad flat face which seals with the top wall X and bead D of the can. The sealing washer 13 has a sufficient degree of "give" or yieldability to conform to the bead D and yet seal with the wall X right up to the bead.

It will be seen that when the cutter 12 is driven or forced through the can wall X that the washer 13 is pressed against the end of the can. The force required to drive the cutter 12 through the can wall X carries the washer 13 into tight cooperation with the can. However, when the downward movement and thrust on the device is stopped, at the completion of the can opening operation, the resiliency of the washer 13 tends to back the device off, that is, it tends to slightly raise the device and thus release the pressure with which the washer bears on the can.

The means 14 acts to automatically lock or latch the device in the position on the can C where the washer 13 is tightly compressed against the end of the can to have effective sealing cooperation therewith so that there will be no leakage of fluid from around the pouring opening or from around the spout 10 when the can is inverted to pour out its contents. The means 14 comprises a simple latch 34 in the form of a lever. The latch 34 is arranged at the inner side of the guide 11 to be within or partially within its groove 33. As illustrated the latch 34 extends longitudinally of the groove 33 and has its upper end at or adjacent the can bead D, assuming the device to be

in the final position on the can C. The latch 34 is preferably channel-shaped in cross section to increase its strength and to better conform to the groove 33 and the exterior of a cylindrical can or the corner of a polygonal can. The longitudinal edges of the latch 34 are downwardly convergent so that the latch is of downwardly diminishing width. These convergent longitudinal edges of the latch 34 are preferably bevelled or pitched in such a way that they generally conform to the external surface of the can C. The above-mentioned groove 33 is shaped and proportioned to substantially entirely receive the latch 34 when the latch is pressed outwardly through its engagement with the can C. The latch 34 is provided with a dent, dimple or raised part which forms a fulcrum 35 adapted to bear in the groove 33 of the guide 11. The fulcrum 35 for the lever-like latch 34 is spaced a short distance above the lower end of the latch.

Means is provided for yieldingly urging the major portion or upper arm of the latch 34 inwardly or toward the can C. This means includes a stem 36 which projects outwardly from the lower end of the latch 34. The stem 36 may be an integral part of the latch and projects outwardly through an opening 37 in the guide 11. The stem 36 is preferably flat or polygonal in transverse cross section and the opening 37 is correspondingly shaped so that the cooperation of the stem with the opening assists in holding the latch 34 in the vertical or upright position. A cotter key 38 or the equivalent is passed through an opening in the outer portion of the stem 36 and a washer 39 is engaged on the stem 36 at the inner side of the cotter key. A coiled spring 40 is arranged around the stem 36 and is held under compression between the washer 39 and the outer surface of the guide 11. It will be seen that the spring 40 acting outwardly on the washer 39 urges the upper arm or portion of the latch 34 inwardly or toward the can C.

The latch 34 is formed to have effective latching engagement with the bead D of the can C. The upper end of the latch 34 is provided with upwardly projecting fingers 41 for engaging under the bead D. The fingers 41 are pointed and pitched upwardly and inwardly to effectively bite or lock under the bead D. When the cutter 12 is forced through the wall X of the can C the engagement of the latch 34 with the can pivots the latch outwardly and the latch travels down past the bead D. When the cutter reaches or approaches the end of its downward movement the fingers 41 move downwardly past the bead D and as soon as their upper ends clear the bead the spring 40 acting outwardly on the lower part of the latch swings the upper arm of the latch inwardly so that the fingers 41 are moved under the bead D to latch the same. The fingers 41 are positioned and related to the other parts so that their cooperation with the under side of the bead D holds the washer 13 compressed against the top of the can as illustrated in Fig. 2.

Means is provided for releasing the latch 34 so that the can spout may be removed from the can C when the contents have been drained from the can. A handle 42 is provided on the upper end of the latch 34. The handle 42 projects outwardly from between the spaced fingers 41 and passes out through an opening 43 in the guide 11. The handle 42 is flat or polygonal in transverse cross section and the opening 43 is in the form of a horizontal slot to receive the flat handle so that the cooperation of the handle with the open-

ing prevents excessive tilting of the latch and maintains the latch in its vertical position. In this connection it should be observed that the engagement of the stem 36 and the handle 42 in their respective openings 37 and 43 effectively retains the latch 34 in its operative position. The handle 42 may project some distance from the outer side of the guide 11 and is shaped to be readily pressed downwardly by the thumb or a finger of the hand which grips the spout 10.

It is believed that the operation of the can spout provided by this invention will be readily understood from the foregoing detailed description. In opening the can the lower portion of the guide 11 is engaged against the bead at the top of the can C to bring the cutter point 20 against the top can wall. The operator grasping the handle and spout 10 then presses the device down with considerable force. This drives the cutter 12 through the can wall X to form the pouring opening therein. When the cutter 12 is piercing the can wall X the guide 11 is moved downwardly at the outer side of the can and the latch 34 is likewise moving downwardly at the exterior of the can. The upper portion of the latch 34 rides down on the bead D and the can wall. When the device approaches its final position the washer 13 comes into engagement with the top of the can and is compressed against the can wall X and the bead D. The final downward movement of the device moves the latch fingers 41 below the bead D and the spring 40 swings the upper end of the latch inwardly so that the latch fingers 41 are moved under the bead D. When the downward pressure or force is removed from the device the resiliency of the compressed washer 13 tends to raise the device or back it away from the can. The fingers 41 engaged under the bead D prevent this. Accordingly, the washer 13 is maintained compressed, that is, it is held tight against the top can wall X and bead D. The compressed washer 13 effectively prevents the leakage of even the very lightest of fluids from around the cutter 12 and when the can C is inverted or tipped to pour out its contents through the spout 10 there is no leakage around the pouring opening or down around the spout 10. It will be apparent how the washer 13 held in tight pressural engagement with the can prevents the leakage of the fluid.

The washer 13 held in compression-engagement with the top wall of the can effectively seals with the can even though the wall may be bent or distorted or may have ridges or corrugations.

When the can spout is to be removed from the can C the operator grasps the handle and spout 10 and presses downwardly on the handle 42. The downward pressure of the handle 42 swings the upper portion of the latch 34 outwardly to free the latch fingers 41 from the bead D. The latch 34 pivots on its fulcrum 35. With the fingers 41 released from the bead D the device is moved upwardly to withdraw the cutter 12 and free the device from the can C. While the device is shown used on a cylindrical can it is to be understood that it may be employed to open square or polygonal cans, in which case the cutter 12 is forced through a corner portion of the can top.

Fig. 7 illustrates a slightly modified form of latch 34a. The latch 34a is designed to obtain effective latching engagement with the can bead D in either one of two slightly different vertical positions. The latch 34a may be substantially the same as the latch 34 described above having

an elongate body portion that is arcuate or channel-shaped in transverse cross section and provided at the lower end with a stem 36a and at its upper end with a handle 42a. An outwardly projecting fulcrum 35a is pressed or otherwise provided in the lower portion of the latch body. The upper end of the latch 34a is provided with upwardly projecting somewhat sharpened latch noses or fingers 41a for latching under the can bead D. The parts of the latch 34a thus far described have functions corresponding to the corresponding elements of the above described latch 34.

The latch shown in Fig. 7 is characterized by 15 a latch tongue 50. The tongue 50 may be formed by making a substantially U-shaped cut in the latch adjacent its upper end and striking or pressing the material inwardly at the opening to project from the inner side of the latch and thus constitute the tongue 50. The upper edge of the tongue may be somewhat sharpened or bevelled. As clearly shown in Fig. 7 of the drawings the latch tongue 50 projects inwardly to the same extent or to a greater extent than the latch fingers 41a and is designed to latch under the bead D. Further, as clearly illustrated, the latch tongue 50 is spaced below the latch fingers 41a. The tongue 50 is provided to latch with the bead D in the event that the latch fingers 41a do not obtain latching engagement with the bead.

The operation of the latch shown in Fig. 7 is substantially the same as that of the latch 34. When the cutter 12 is driven down through the 35 end wall X of the can the latch 34a rides down past the bead D. Near the end of the can-opening operation the washer 13 is forced against the upper wall of the can and the tongue 50 moves downwardly below the bead D. In most cases the latch fingers 41a will also be moved down 40 past the bead D to obtain latching engagement with the bead when the can-opening operation terminates. However, in some cases, the latch fingers 41a may not reach positions where they 45 can engage under the bead D. In such cases the latch tongue 50 comes into engagement with the under side of the bead D to latch the can spout on the can in a position where the washer 13 is in effective sealing engagement with the can.

Figs. 8, 9 and 10 of the drawings illustrate a 50 form of latch for embodiment in the can spout of the invention, which latch is constructed to obtain effective latching engagement with the can bead D at a plurality of different elevations, that is, when the can spout is forced downwardly to varying extents in the process of opening the can. The latch 34b of Figs. 8, 9 and 10 is generally the same as the above described latch 34 having an elongate body portion that is channel-shaped or arcuate in transverse cross section. A stem 36b projects outwardly at the lower end of the latch and a handle 42b projects outwardly at the upper end of the handle. A fulcrum projection 35b is provided on the outer side of the latch body adjacent its lower end. The longitudinal edges 51 of the channel-shaped or arcuate latch body are preferably bevelled off or flattened to lie substantially flush against the side wall of the can C when the latch is in its operative position against the can. In this form of the invention each longitudinal edge portion of the arcuate latch body is provided with two or more spaced niches 52 which provide or define teeth 53. The niches 52 are shaped so that the teeth 53 are sharp and project upwardly and inwardly. In practice, the teeth 53 may resemble

saw teeth. While I have shown only two teeth 53 on each longitudinal edge of the latch 34^b it is to be understood that a larger number of teeth may be provided. The teeth 53 at the opposite sides of the latch lie in corresponding planes.

Where the latch 34^b of Figs. 8, 9 and 10 is employed the operation of the device is the same as above described except that the latch 34^b is effective even though the uppermost pair of teeth 53 fails to obtain latching engagement under the can bead D. In the use of the can spout the operator may exert insufficient downward force to compress the washer 13 against the can to a sufficient extent to bring the uppermost teeth 53 under the bead D or to a position where they can obtain proper latching engagement with the bead. Furthermore, the construction of the can C may be such that the uppermost teeth 53 will not obtain full holding engagement with the bead D. In such cases the lower teeth 53 come into effective latching engagement with the under side of the bead D when the cutter actuating downward pressure is removed from the device. The lower teeth 53 are positioned so that their engagement with the bead D maintains the washer 13 in firm sealing engagement with the can C, with the washer compressed to be fully effective. Where the latch 34^b of Figs. 8, 9 and 10 is embodied in the can spout the can spout has a wide range of utility, being adapted for use on cans varying considerably in construction and assuring the effective dependable sealing action of the washer 13 in instances where the cutter has not been completely actuated.

Figs. 11 and 12 illustrate a form of latch 34^c adapted to be embodied in the can spout. The latch 34^c has an elongate generally vertical body of arcuate or channel-shaped cross section with a stem 36^c projecting outwardly from its lower end and a suitable handle 42^c projecting outwardly from its upper end. A fulcrum 35^c is formed on the outer side of the latch body adjacent its lower end. The parts just described have functions corresponding to the functions of the corresponding parts fully described above. The longitudinal edges 55 of the curved or channel-like latch body are bevelled or flattened to better conform to the external wall of the can C. The upper ends of the latch side walls terminate at abrupt shoulders 56 and 57. These shoulders 56 and 57 are operable to engage or latch under the bead D of the can. In accordance with this form of the invention one shoulder, say the shoulder 56, occurs at a higher elevation than the shoulder 57. When the can spout is used the latch 34^c moves down past the bead D, as above described, and when the cutter 12 approaches the end of its movement the shoulders 56 and 57 approach or pass the bead D. If the cutter C is completely actuated, that is, forced down to its extreme lowermost position the highest shoulder 56 is moved to a position below the bead D. When the downward pressure is removed from the device the resiliency of the washer 13 tends to raise or back the device off and the engagement of the shoulder 56 with the bead D limits and stops this action and holds the washer 13 under compression against the upper can wall X to preserve a tight sealing engagement. On the other hand, the cutter 12 may not be fully actuated or the can structure may be such that the cutter does not assume an extreme down position. In this latter case the shoulder 56 may not reach a position to engage under the bead D but the lower shoulder 57 will have assumed a position to engage under

the bead D. Accordingly, when the downward actuating pressure is relieved from the device the shoulder 57 automatically engages under the bead D to latch the device on the can in a position where the washer 13 is compressed against the upper can wall. The fulcrum 35^c is such that the latch 34^c may have limited rocking or tilting movement providing for the automatic engagement of the individual shoulders 56 and 57 with the bead D.

It is to be understood that the latches illustrated in Figs. 7 to 12, inclusive, are automatically actuated or urged to their operative positions by the spring 40 and may be readily released by the user or operator by pressing against their respective handles 42^a, 42^b and 42^c, these operations being the same as described in connection with the form illustrated in Figs. 1 to 6, inclusive.

Having described typical preferred forms and applications of my invention, I do not wish to be limited or restricted to the specific details herein set forth, but wish to reserve to myself any variations of modifications that may appear to those skilled in the art or fall within the scope of the following claims.

Having described my invention, I claim:

1. A device for opening a can which has a side wall and top joined by a bead, the device including a sheet metal body having a pouring spout and a guide continuous with the spout for cooperating with the wall of the can, the spout and guide being in substantial alignment and the spout being in the form of a handle for manipulating the device and projecting up from the top of the can when the device is applied to a can, a cutter on the body substantially parallel with the guide and spout adapted to cut an opening in the top of the can from which the contents may be poured through the spout, a resilient compressible sealing member on the body surrounding the base of the spout so it is compressed against the top to seal around the cutter when the cutter is forced to its final position, a flange on the body overlying the sealing member and confining it to an operating position, a rigid latch arranged at the inner side of the guide to project upwardly between the guide and cutter, means connecting the lower end of the latch with the body for movement relative thereto, the latch having a fulcrum for bearing on the guide, spring means at the lower end of the latch for urging the latch to a position where its upper end latches under the bead when the cutter approaches its final position so that the latch holds the device in the position where the sealing member is compressed, and means for releasing the latch including a part projecting from the upper end portion of the latch so it is accessible at the exterior of the guide.

2. A device for opening a can which has a side wall and top joined by a bead, the device including a body having a pouring spout and a guide for cooperating with the wall of the can, a cutter on the body adapted to cut an opening in the top of the can from which the contents may be poured through the spout, a resilient compressible sealing member on the body that is compressed against the top to seal around the cutter when the cutter is forced to its final position, a flange on the body overlying the sealing member, a lip on the flange confining the sealing member to the flange, a rigid latch extending upwardly at the inner side of the guide, means pivotally mounting the latch on the guide including a projection on the lower end of the latch carried in an opening in the guide, spring means at the lower end portion of the latch

11

for urging the latch to a position where its upper end latches under the bead when the cutter approaches its final position so that the latch holds the device in the position where the sealing member is compressed, and a releasable handle on the latch extending from the upper end of the latch through an opening in the guide to project laterally from the guide so it is accessible at the exterior of the guide.

3. A device for opening cans including a cutter adapted to be forced through the top of the can to form a pouring opening therein, a spout extending from the outer end of the cutter to be parallel therewith for conducting away the contents of the can, means at the outer end of the cutter adapted to have sealing engagement with said wall around said opening, including an annular sealing member and a flange located where the cutter joins the spout and overlying the sealing member and latch means in connection with the cutter and spout for cooperating with the can to hold the sealing means in engagement with said wall, the latch means comprising a vertically disposed latch having vertically spaced upwardly facing shoulder parts at its upper end for latching with the can in different vertical positions of the device relative to the can.

4. A device for opening a can which has a side wall and top joined by a bead, the device including a body having a pouring spout and a guide for cooperating with opposite sides of the side wall of the can, a cutter on the body substantially parallel with the guide and adapted to cut an opening

12

in the top of the can from which the contents may be poured through the spout, a sealing member on the body around the base of the spout for sealing with said other wall around the cutter including an annular sealing member and a flange located where the cutter joins the spout and overlying the sealing member, the flange having a lip confining the sealing member and means on the body for latching the bead to hold the sealing member in sealing engagement with said other wall, said means including a rigid vertically disposed latch pivotally supported at the inner side of the guide and adapted to ride down past the bead when the cutter is forced through the top of the can, and vertically spaced upwardly facing shoulder parts on the latch for latching under the bead with the device at different elevations on the can.

OZRO N. WISWELL.
